UNITED STATES PATENT OFFICE

2,132,093

LIQUID HEATER

Clement K. Bennett, Philadelphia, Pa., assignor
to C. H. Wheeler Manufacturing Company,
Philadelphia, Pa., a corporation of Pennsylvania

Application January 14, 1937, Serial No. 120,533

8 Claims. Cl. 257—225

This invention relates to a liquid heater and particularly to a water heater to which steam is applied during the blow down of wood fiber digesters.

5 In normal operation digesters are operated at about 100 lbs. per square inch pressure and are arranged to cook wood fiber for extended periods of time, normally around two or more hours. At the end of the cooking period the pressure is 10 reduced to about 75 lbs. per square inch and the blowing takes place at such pressure. The contents of the digester during the blowing operation are discharged into a tank having approximately one and one-half times the capacity 15 of the digester, the blowing taking from eight to fifteen minutes time. In general the blow down may occur approximately every six hours from a single digester.

From the blow down tank the steam which is 20 formed is generally passed through a separator into a blow down heater wherein the latent heat content is recovered and used for heating process water or other liquid.

It sometimes happens that operators are careless about the liquid level in the blow tank or in the manner of blowing and the liquid level may then reach too high a level in the blow tank, in which case liquor is blown over into the heater. When this occurs the paper pulp contained in 30 the liquor quickly fouls and plugs the heat exchange surfaces and the efficiency of the heater is very much reduced. Even if the liquor is not blown over due to too high a liquor level, the flashing of water into steam takes place almost 35 explosively and the rapidity of flow causes a carrying over into the heater of very considerable quantities of the wood fiber which will be deposited upon the heat exchange surfaces of the heater.

40 As a result of the fouling which thus occurs ample provision must be made in properly designed blow down heaters to permit periodic washing down of the surfaces, this wash down preferably occurring between blows by means of water under pressure. Means must also be provided for sluicing the surfaces with a high pressure hose inserted through the shell, this latter operation taking place when results indicate that 45 the surfaces are badly fouled.

50 Due to the fact that the heater is cold for extended periods and then receives a certain rush of steam the construction must be such as to cause it to stand severe temperature changes 55 without distortion or weakening, ample provi-

sions being made for free expansion and contraction of the tubes which it contains.

Heretofore it has been generally customary to use substantially an ordinary surface condenser as a blow down heater with some additional provision for the insertion of a hose to wash off the tubes. The arrangement of tubes in the conventional surface condenser is by no means satisfactory in such cases since in general it is found that while high pressure water may remove the 10 wood fiber from the tubes nearest its inlet, it may serve to compact the wood fiber even more into remoter locations. Furthermore, the conventional surface condenser must be specially made to provide for uneven expansion necessitated by 15 the very rapid impingement of steam upon cold surfaces. The multiple passes of the cold water which is being heated are also generally arranged in a fashion which contributes in causing asymmetrical stresses to be set up in the heater. 20

It is a general object of the present invention to provide an improved liquid heater (generally for heating water) designed for use in conjunction with the blowing down of wood fiber digesters. In the attainment of this object provision is made first for the reduction of the strains 25 incidental to the very rapid heating of a cold apparatus by insuring that the heating takes place in a symmetrical fashion with respect to the mechanical structure. This is accomplished 30 by providing radial symmetry for the multiple liquid passes together with a single passage of the steam in such fashion that substantially all of the steam is caused to first impinge upon the hottest tubes from which the water flows out 35 of the heater. Ample provision is also made for permitting the expansion which will result without the imposition of great strains upon the structure.

Secondly, provision is made for the complete 40 and easily accomplished cleaning of the surfaces of the tubes. This end is accomplished by reason of the radial symmetry of the arrangement in conjunction with the provision of suitable passages for high pressure liquid introduced from 45 the outside of the shell and also by the strategic location of wash down nozzles for causing washing water to flow downwardly along the vertical tubes in such fashion as to reach and wash all of them. 50

Other objects of the invention relate primarily to details of construction which will be apparent from the accompanying drawings in which Figure 1 is an elevation of a heater constructed in accordance with the invention, certain parts be- 55

ing broken away and shown in section to clarify the internal construction.

Figure 2 is a section taken as indicated at 2-2 in Figure 1;

5 Figure 3 is a plan view of the heater showing the manifolding of the wash down nozzles;

Figure 4 is a vertical section showing the arrangement and construction of a wash down nozzle;

10 Figure 5 is a fragmentary vertical section taken on the plane indicated at 5-5 in Figure 1; and

Figure 6 is a fragmentary section showing specifically the mode of connecting the floating tube plate and its cover.

15 The heater comprises a shell 2 extended at its lower end, as indicated at 4, into a non-condensable gas belt 6 provided with a gas outlet 7. The provision of the skirt provided by the extension 4 prevents to a considerable extent the carrying out 20 with non-condensable gases of steam condensate. The lower wall of the belt 6 may be made square so as to provide corners extending beyond the circular portions of the apparatus to provide feet on which the apparatus may be supported.

25 A lower outside shell cover 10 is provided having a condensate outlet 12. This is secured to the underside of the plate 8.

The upper end of the shell 2 is continued as indicated at 14 and 15. The first continuation 14 30 provides a steam impingement baffle cut away at its lower corners, as indicated at 16, to permit the reaching of the tubes by the stream from a washing nozzle. Surrounding the upper end of the shell and extending somewhat below the extension 15 is an eccentric belt 18 provided at its point of maximum diversion from the shell with a steam inlet indicated at 20. The baffle 14 is opposite this steam inlet and causes the steam to flow laterally within the eccentric belt 18 so 35 that it is distributed substantially uniformly to the periphery of the tube bundle. The belt 18 is provided with a bottom plate 22 shaped to fill the space between the outer wall of the belt and the shell 2. Drain openings 24 are provided in 40 this plate 22, these openings being normally covered by suitable cover plates bolted thereto.

The top 26 of the belt 18 serves to support the fixed tube plate 28, which in turn is surmounted by the water distributing head 30. This head is 45 provided with a water inlet passage 32 feeding water into a central pass of tubes, an annular connecting passage 34 and an outer annular water discharge passage 36. The construction shown is designed to provide four water passes, the water or other liquid being led first to the innermost 50 pass and then successively through the intermediate passes to the outermost one, from which it is discharged into the passage 36. The symmetrical arrangement of the successive passes is indicated in Figure 2. The tube bundle at its lower 55 end supports the floating tube plate 40, which is provided with a cover 42 containing suitable partitioning means to provide connections between the first and second and the third and fourth passes, as indicated at 48 and 50. A central opening 46, through the cover, is aligned with a central opening 44 through the tube plate 40 to provide for the passage of condensate into the cover 10.

70 The connection between the floating cover 42 and the tube plate 40 is worthy of note and is indicated on an enlarged scale in Figure 6. The connection is made by means of a series of hook bolts generally indicated at 52 and comprising 75 upper hook ends 56 forwarded integral with bolt

extensions 58 threaded to receive nuts 60. The heads 56 are provided with hook elements 61 designed to be received in an annular groove 62 formed adjacent the periphery of the upper surface of the plate 40. By turning the hook members 61 to an outer position the cover 42 may be aligned with the plate 40 with the interposition of a gasket indicated at 64. The heads 56 may then be turned to cause the hook members 61 to enter the groove 62, whereupon the bolts 60 may be tightened to secure the cover 42 to the plate. It will be noted that wherever tight connections are required annular gaskets are set into grooves to prevent blowout. Besides the connection by means of the hook bolts, there are provided stay bolts between the cover 42 and tube plate 40.

Nozzles 66 are provided in proper locations relative to the tubes to introduce the necessary water for washing down the outside of the tubes. These nozzles 66 are shown in Figure 4 and comprise vertically extending pipes carrying distribution nozzles 68. Each of the pipes is threaded into a coupling 70 secured by a member 72 to the upper end of a tube 74 welded to the cover 30 and drawn down by means of stay bolts 78 in contact with the upper fixed tube sheet 28 with the interposition of suitable gaskets such as indicated at 76 to prevent leakage. Distribution of wash water to the nozzles is provided through a manifolding arrangement, indicated at 8, receiving the 30 water from a common inlet 82. The pipes of this manifolding arrangement are graduated, as indicated in Figure 3, to insure that all the nozzles receive an adequate supply of water under pressure to insure proper cleaning of all of the tubes. 35 It will be noted from Figure 2 that the tubes 38 are so arranged as to provide a series of eight radial passages which are substantially clear into the innermost pass of tubes throughout the entire vertical extent of the heater. Opposite 40 these passages there are provided openings 84 normally closed by covers 86 against which press adjustable screws 88 threaded into levers 90 pivoted at 92 and arranged to be held in their closing positions by means of loop members 94. 45 The covering arrangement just described is readily opened and closed by manipulation of the loop members 94 and screws 88. Through the openings 84 there may be manipulated high pressure water streams for the purpose of reaching and cleaning the tubes when the accumulation takes place to such extent that the nozzles at the uppermost portion of the apparatus may be ineffective to provide complete cleaning. The 50 passages, it will be noted, have between them only 55 relatively small numbers of the tubes, with the result that streams of washing water introduced into any passage will readily effect the washing out into an adjacent passage of accumulated fiber. However, the nozzles 66 are primarily depended 60 upon for washing down purposes. These nozzles are located within the groups of tubes between the passages and serve to wash out the accumulated material into the passages, whence it will flow down and out the opening 46.

A considerable accumulation of fiber and other sediment will occur in the channel formed between the extension 15 of the shell 2 and the outer wall of the belt 18. Such accumulation may be readily washed out through the openings 70 24 by the insertion of a hose into the various openings 84 formed in the belt.

The construction has been specifically described as applied to a four pass liquid arrangement. It will be obvious that a similar construction will 75

be applicable to single or other multiple pass arrangements, suitable changes being made in the headers to secure the proper flow.

The fact that the cold liquid enters the center 5 and flows to the outside through the successive passes and that the passes are arranged annularly around the center insures a symmetrical distribution of stresses when expansion and contraction take place to prevent any tendency toward lateral buckling of the structure. The symmetry of the stresses is also promoted by the distribution of the steam in the eccentric belt 18, which, together with the baffle 14, produces a flow of the steam so as to substantially equally 10 distribute it to all of the outer tubes of the last liquid pass. It will be noted that a counterflow arrangement is substantially provided to further minimize the stresses and promote efficiency.

While an arrangement having a steam inlet at 20 the top has been specifically described and is preferable because there is no counterflow of condensate and steam, it is also feasible to cause the steam to enter at the bottom and flow upwardly. In both cases condensate will run down 25 the tubes and aid to some extent in preventing the deposition of fiber or other sediment.

It may be remembered that the steam carries over with it both volatile and non-volatile materials, which may be of a corrosive nature, and 30 depend upon the particular digestion process which is used. Consequently, the tubes and the other parts which come into contact with such corrosive materials should be made of suitable metal to withstand the corrosive action.

35 What I claim and desire to protect by Letters Patent is:

1. A heat exchange apparatus comprising an outer shell, a passage for the introduction of gas into the shell, a series of tubes extending longitudinally within the shell, and connections between groups of tubes to provide a multiple pass arrangement providing at least three passes, the groups of tubes forming the successive passes being circularly and concentrically arranged, the 40 gas spaces about the various groups being in free communication with each other throughout the lengths of the tubes.

2. A heat exchange apparatus comprising an outer shell, a passage for the introduction of gas into the shell, a series of tubes extending longitudinally within the shell, and connections between groups of tubes to provide a multiple pass arrangement providing at least three passes, the groups of tubes forming the successive passes being circularly and concentrically arranged with the final pass outermost, the gas spaces about the various groups being in free communication with each other throughout the lengths of the tubes.

3. A heat exchange apparatus comprising an outer shell, a passage for the introduction of gas into the shell, a series of tubes extending longitudinally within the shell, connections between groups of tubes to provide a multiple pass arrangement providing at least three passes, the groups of tubes forming the successive passes being circularly and concentrically arranged and means for distributing the introduced gas mainly to the outermost group, the gas spaces about the various groups being in free communication with

each other throughout the lengths of the tubes.

4. A heat exchange apparatus comprising an outer shell, a passage for the introduction of gas into the shell, a series of tubes extending longitudinally within the shell, and connections between groups of tubes to provide a multiple pass arrangement, the groups of tubes forming the passes being concentrically arranged longitudinally within the shell, said tubes being arranged in groups with passages between the groups, and washing nozzles arranged to direct liquid along the tubes within the groups to wash material therefrom into said passages.

5. A heat exchange apparatus comprising an outer shell, a passage for the introduction of gas into the shell, a series of tubes extending vertically within the shell, and connections between groups of tubes to provide a multiple pass arrangement, the groups of tubes forming the passes being concentrically arranged vertically within the shell, said tubes being arranged in groups with vertically clear passages between the groups, and washing nozzles arranged to direct liquid downwardly within the groups to wash material therefrom into said passages.

6. A heat exchange apparatus comprising an outer shell, a passage for the introduction of gas into the shell, a series of tubes extending longitudinally within the shell, and connections between groups of tubes to provide a multiple pass arrangement, the groups of tubes forming the passes being concentrically arranged longitudinally within the shell, said tubes being arranged in groups with radial passages between the groups, and openings in said shell aligned with the 30 passages for the introduction of washing liquid to force accumulated material from the tubes into said passages.

7. A heat exchange apparatus comprising an outer shell, a passage for the introduction of gas into the shell, a series of tubes extending longitudinally within the shell, and connections between groups of tubes to provide a multiple pass arrangement, the groups of tubes forming the passes being concentrically arranged vertically within the shell, said tubes being arranged in groups with vertically clear radial passages between the groups, and openings in said shell aligned with the 40 passages for the introduction of washing liquid to force accumulated material from the tubes into said passages.

8. A heat exchange apparatus comprising an outer shell, a passage for the introduction of gas into the shell, a series of tubes extending longitudinally within the shell, and connections between groups of tubes to provide a multiple pass arrangement, said connections including means joining the lower ends of the tubes provided with a central wash-out port, the groups of tubes forming the passes being concentrically arranged vertically within the shell, said tubes being arranged in groups with vertically clear radial passages between the groups of the outer passes, and openings in said shell aligned with the 50 passages for the introduction of washing liquid to force accumulated material from the tubes into said 55 passages, the group of tubes forming the innermost pass surrounding a vertical space, clear of tubes, aligned with said wash-out port.
